UNITED STATES PATENT OFFICE

GEORGE F. REINAGEL, OF BUFFALO, NEW YORK

DESIGN FOR A RACK FOR HOLDING NEWSPAPERS OR THE LIKE

Application filed April 30, 1932. Serial No. 43,675. Term of patent 3½ years.

To all whom it may concern:

Be it known that I, GEORGE F. REINAGEL, a citizen of the United States, residing at Buffalo, in the county of Erie and State of New York, have invented a new, original, and ornamental Design for a Rack for Holding Newspapers or the like, of which the following is a specification, reference being had to the accompanying drawing, forming part thereof.

In said drawing:

Figure 1 is a front elevation of a rack for holding newspapers or the like showing my new design.

Figure 2 is a side elevation.

Figure 3 is a perspective view.

I claim:

The ornamental design for a rack for holding newspapers or the like substantially as shown.

GEORGE F. REINAGEL.
